UNITED STATES PATENT OFFICE.

WILLIAM RUNNING, OF DETROIT, MICHIGAN.

ELECTRICAL APPARATUS FOR TREATING DISEASES.

Application filed March 5, 1923. Serial No. 622,803.

To all whom it may concern:

Be it known that I, WILLIAM RUNNING, a subject of the King of Great Britain, residing at Detroit, in the county of Wayne 5 and State of Michigan, have invented certain new and useful Improvements in Electrical Apparatus for Treating Diseases, of which the following is a specification, reference being had therein to the accompanying drawings.

The primary object of my invention is to provide an electrical apparatus by which patients may safely receive electric treatment for various kinds of diseases, the apparatus permitting of a human body being placed in an electric oscillatory or vibratory circuit without having direct connection with the source of electrical energy.

Another object of this invention is to provide an electrical apparatus including a plurality of electrical instruments for regulating and controlling the use of an electrical current in the treatment of diseases, the various instruments being compactly 20 assembled in a cabinet having an instrument board, supporting a majority of the electrical instruments on the inner wall thereof with operating instrumentalities on the outer wall of the instrument board so 25 that electrical connections may be easily established and the operation of the apparatus easily regulated.

A further object of this invention is to accomplish the above results by a novel arrangement of electrical instruments and devices which will be hereinafter specifically described and then claimed, and reference will now be had to the drawings, wherein—

Figure 1 is a front elevation of the electrical apparatus, partly broken away to show condenser connections;

Fig. 2 is a horizontal sectional view of the apparatus;

Fig. 3 is a vertical cross sectional view of the same, and

Fig. 4 is a diagrammatic view of the electrical instruments, devices and wiring entering into my invention.

I provide a cabinet or a box-like structure composed of a base or bottom wall 1, end walls 2, a rear wall 3, a hinged top wall or lid 4, and a front wall or instrument board 5. The walls 1 to 4 inclusive may be made of wood and the instrument board 5 of hard rubber or any suitable insulation material. The instrument board 5

is detachably held by screws 6 or other fastening means so that it can be easily removed should occasion require.

In the cabinet, parallel to the rear wall 60 3 is a partition 7 providing a chamber 8 for a condenser composed of grid frames 9 separated by a partition 10 made of any suitable insulation material, as hard rubber or fiber and said partition serves as a dielectric for grids 11 and 12 mounted in the frames 9.

Mounted on the instrument board 5, adjacent the upper edge thereof, are binding posts 13 and 14 for leading-in wires 15. On 70 the outer wall of the instrument board 5 is a holder 16 for a conventional form of cartridge fuse 17 and one end of the fuse holder is connected by a wire 18 to the binding post 13.

Mounted on the inner wall of the instrument board 5 is a bracket or holder 19 for a spark coil or interrupter which may be in the form of an electro-magnet 20 provided with a resilient armature 21 adapted to vibrate relative to a contact member 22. The resilient armature 21 is connected by a wire 23 to a conventional form of switch 24, preferably of the push button type, and said switch is connected by a wire 25 to the 80 binding post 14. The resilient armature 21 is also connected by a wire 26 to a fixed condenser 27 and said condenser by a wire 28 to the contact member 22. The purpose of the fixed condenser is to prevent pitting 90 of the contact points of the contact member 22 and the resilient armature 21.

Mounted on the inner or rear wall of the instrument board 5 are transformer coils 29 and 30 and the coil 29 is connected by a wire 95 31 to one of the terminals of the electro-magnet 20, while the other terminal of said electro-magnet is connected by a wire 32 to the fuse holder 16.

The transformer 29 has both of its coils 100 connected by a wire 33 to one of the terminals 34 of a spark producing device and the other terminal 35 of said device is connected by a wire 36 to the condenser grid 11. One of the coils of the transformer 29 is connected by a wire 37 to a conventional form of ammeter 38 mounted in the instrument board 5, said ammeter being connected by a wire 39 to the contact member 22. The ammeter 38 is employed for measuring large 110 values in connection with the circuit of the transformer 29, in contradistinction to a

milli-ammeter 40, carried by the instrument board 5 and in circuit with the transformer 30. The milli-ammeter 40 is connected by a wire 41 to the condenser grid 12 and by a wire 42 to one of the coils of the transformer 30, the other coil being connected by a wire 43 to a variable condenser 44 carried by the instrument board 5. The variable condenser is connected by a wire 45 to a binding post 46 and said binding post is adapted to be connected by a wire 47 to the ground.

Both coils of the transformer 30 are connected by a wire 48 to one or more binding posts 49 on the instrument board, and one of these binding posts is connected by a wire 48^a to an electrode 49^a adapted to be applied to a human body 50^a for electrical treating purposes. The electrode 49^a may be of any desired form and the human body 50^a has a grounded connection 47^a, so that there is a complete secondary circuit.

One of the electrical circuits may be traced from the binding post 14 through the switch 24 to the resilient armature 21 and the contact member 22, by wire 39 to the ammeter 38, by wire 37 to the transformer 29, wire 31 to the electro-magnet 20, wire 32 to the fuse 17, and wire 18 to the binding post 13.

Another circuit may be traced from the transformer 29 through the spark producing device including terminals 34 and 35, by wire 36 to the condenser grid 11, then from the condenser grid 12 by wire 41 to the milli-ammeter 40 and by wire 42 to the transformer 30. From the transformer 30 through the variable condenser 44 to the binding post 46 and the ground. This last mentioned circuit may be shunted through a grounded human body by one or more electrodes attached to the body and con-

nected to the binding posts 49 which are electrically connected to the transformer 30.

The apparatus will permit of tissues of the human body being subjected to an oscillatory or vibratory electrical current without direct metallic connection with the source of electrical energy, because of the condenser grids interposed between the source of electrical energy and the human body, consequently there is no danger of the human body being shocked or injured by any accidental excessive current of electricity. It is by virtue of the variable condenser and other electrical devices of the apparatus that the electrical treatment may be varied for different diseases, and while in the drawings there is illustrated a preferred arrangement of the electrical devices, I desire it to be understood that there may be other arrangements and such changes as are permissible by the appended claim.

What I claim is:—

An electrical apparatus of the character described, comprising a cabinet having front and rear walls with the front wall formed by an instrument board, a plate of insulation adjacent the rear wall of said cabinet, condenser grids at each side of said plate of insulation, one of said condenser grids being in a leg of an oscillatory current circuit, a ground circuit for the other grid, a transformer in each circuit with the transformer of the ground circuit adapted to be shunted through a grounded body, an ammeter on the instrument board in the oscillatory current circuit, and a milliammeter on the instrument board in the ground circuit.

In testimony whereof I affix my signature.

WILLIAM RUNNING.
